(57) **CLAIM**

The ornamental design for a headset, as shown and described.

DESCRIPTION

FIG. 1 is a top View of a headset showing my new design;
FIG. 2 is a front View thereof;
FIG. 3 is a bottom View thereof;
FIG. 4 is a right side View thereof;
FIG. 5 is a left side View thereof;
FIG. 6 is a rear View thereof; and,
FIG. 7 is a perspective front View thereof, the opposite front face of the headset ear cup is a mirror image.

1 Claim, 7 Drawing Sheets---
